CLAIM

We claim the ornamental design for a container for storing and dispensing wipes, as shown and described.

DESCRIPTION

FIG. 1 is a perspective view of a container for storing and dispensing wipes according to the present design;

FIG. 2 is a back elevation view thereof;

FIG. 3 is a front elevation view thereof;

FIG. 4 is an end elevation view thereof;

FIG. 5 is a second end elevation view thereof;

FIG. 6 is a top plan view thereof; and,

FIG. 7 is a bottom plan view thereof.

The broken lines shown in FIG. 2 represent unclaimed subject matter and form no part of the claimed design.

1 Claim, 6 Drawing Sheets
